FIG. 4.

UNITED STATES PATENT OFFICE.

WILLIAM C. CLARE, OF OSWEGO, NEW YORK.

HENHOUSE.

1,320,204.

Specification of Letters Patent.

Patented Oct. 28, 1919.

Application filed December 9, 1918. Serial No. 265,905.

To all whom it may concern:

Be it known that I, WILLIAM C. CLARE, a citizen of the United States of America, and resident of Oswego, in the county of 5 Oswego, in the State of New York, have invented new and useful Improvements in Henhouses, of which the following, taken in connection with the accompanying drawings, is a full, clear, and exact description.

10 This invention relates to certain improvements in hen houses in which ventilation, sanitation, convenience and general efficiency in properly housing and caring for the fowls are important objects although other specific objects will be brought out in the following description.

In the drawings:-

Figure -1- is a perspective view of a hen house embodying the various features 20 of my invention.

Fig. -2- is a transverse, vertical, sectional view of the same taken on line -2-, Fig. -1-.

Fig. -3- is a horizontal sectional view 25 taken in the plane of line 3-3, Fig. -2-.

Fig. -4- is an enlarged detailed sectional view of a portion of the hen house showing more particularly the roosts and underlying platform and one of the nests.

30 As illustrated, this hen house comprises a rectangular concrete floor -1- preferably of greater length from end to end than its width from front to rear and from the marginal edges of which rise front and rear 35 walls -2- and -3-, opposite end walls -4- and an upright transverse partition -5- extending from the front wall to the rear wall substantially midway between the end walls for dividing the interior of the

40 house into practically equal compartments or chambers in which fowls of different breeds may be kept separated if desired.

A hollow roof -6- of substantially the same or slightly greater area than the floor 45 is supported upon the upper edges of the side and end walls to cover the entire space inclosed thereby and is composed of an upper section -7-, or roof proper, and a sub-section -7'- arranged in spaced relation 50 to form an intervening air-space or ventilating chamber -8-.

The front wall -2- is preferably of greater height than the rear wall -3- and is provided with lower, intermediate and 55 upper openings 9, 10 and 11 for lighting and

ventilating purposes, said openings being provided, respectively, with doors or sashes 9', 10, and 11' hinged to swing about horizontal, parallel axes to their open or closed positions as may be desired, the lower sashes 60 or doors being hinged substantially midway between their upper and lower edges while the intermediate and upper doors or sashes 10' and 11' are preferably hinged along their upper edges.

The upper opening 11 and its swinging door 11' are directly under the eaves of the roof and preferably extend from end to end of the building and downwardly to approximately the horizontal plane of the upper edge of the partition -5- which latter is of less height from the floor than the front wall -2- so as to leave a clear open space between the upper edge of the partition and the overlying portion of the lower roof 70 plate -7'- as shown more clearly in Fig. -2-, thereby allowing a free circulation of air from one compartment or chamber to the other above the partition.

The rear wall -3- is hollow from the 80 roof down to within a relatively short distance from the floor -1- thus forming an air chamber -8'- communicating with the roof chamber -8-, the inner side of said wall being somewhat narrower vertically 85 than the outer side to afford an air passage -12- connecting the interior compartments of the house with the air passage -8'- along the floor whereby the foul air may find a ready exit through said passage 90 12, 8' and 8 thence through ventilating openings -13- or a flue -14- leading from the larger portion of the chamber -8- to the atmosphere.

It is now clear that the compartments of 95 the house may be easily and quickly ventilated by simply opening one or more of the doors or windows in the front wall of the house and allowing the fresh air to pass through the compartments and out through 100 the exits 12, 8' and 8 and 13 or 14.

The upper roof plate is gabled near the front of the building so that the rear portion thereof inclines gradually from the gable toward the rear and is of much greater 105 length than the portion at the front of the gable which inclines more abruptly or at a greater angle than the rear portion.

The front half of the underlying roof plate -7'- lies in a substantially hori- 110

zontal plane between the gable of the upper plate and upper edge of the partition —5— co-incident with the upper edge of the front wall —2—, the rear half of said inner roof plate being declined rearwardly in a plane substantially parallel with the rear portion of the upper plate.

This construction of the roof makes the front half of the chamber —8— of considerably greater capacity than the rear half to reduce to a minimum the rapidity of movement of the escaping air currents and thereby avoiding dangerous drafts along the floor and other parts of the compartments where the fowls may be assembled.

These ventilating chambers 8 and 8' extend from end to end of the building and therefore communicate with both compartments thereof through the passages —12— 20 near the floor so as to permit the escape of the foul air near the level of the main source of contamination although similar provisions are made at higher elevations as for example through the passages —12'— at 25 approximately the level of the elevated roosts, as —15—, and underlying catch-plates —16— which receive the deposits from the fowls on the roosts.

The partition —5— and one of the end walls —4— are provided with upright doors —17— and —18— near the front wall —2— to permit access of the attendant to the building and to the compartments thereof.

The roosts —15— and underlying catch plate —16— extend from end to end to the building near the rear side thereof but are divided midway between their ends into two sections, each of which is hinged to the inner plate of the rear wall to swing vertically.

40 Each roost section comprises a pair of lengthwise parallel bars —19— secured in spaced relation by screws —20— to a series of underlying transverse parallel rods —21—, the latter being also spaced apart 45 longitudinally of the house and have their rear ends hinged at —22— to the front plate of the rear wall —3— directly above the passage —12'— so that the forward ends of the roost sections may be rocked upwardly 50 away from the underlying catch plate —16— to permit thorough cleansing of all parts of the roosts and also to permit more convenient access to the plate —16— for cleaning purposes.

55 The plate sections —16— are also hinged along their rear edges at —23— to the inner upright plate of the rear wall —3— directly below the passage —12'— to permit its forward end to swing upwardly from a normal 60 horizontal position and thereby to further facilitate the cleaning thereof.

Suitable frame sections —24— are secured lengthwise of the housing to and between the opposite end walls —4— and partition —5— so as to lie in the same horizon-

tal and vertical planes, end to end directly under the front portion of the plate —16— apart therefrom and from the inner plate of the rear wall so as to leave a clear open space between the rear side of said frame 70 and the overlying plate —16— and rear wall —3— through which the fowls may readily pass into the nests, said frame —24— consisting of front and rear walls —25— and —26— in spaced parallel relation and a screen bottom —27— thus forming a lengthwise space which is divided at regular intervals by transverse partitions —28— to form a series of nests in which the fowls may lay their eggs and also to support the free edges 80 of the plates —16—.

The lower rear side of the frame —24— is provided with a rearwardly projecting ledge —29— upon which the fowls may rest temporarily in selecting their nests.

85 Direct communication between the several nests and interior of the compartments at the front thereof is normally cut off by doors —30— which are hinged at —31— to the upper edges of the front walls —25— of the frame —24— to swing forwardly and downwardly, the upper edge of said doors normally closing against the partitions —28— and at the same time excludes excessive light from the nests when the door is 90 in an operative position, or, when opened, permits easy access to the nests for the removal of eggs from the front.

95 The roost —15— is provided at intervals throughout its length with suitable legs 100 —33— preferably directly under the bars —19— and adapted to rest upon the plate —16— for supporting the roost in a horizontal position when the free edge of the plate rests upon the upper edge of the partitions —28—.

105 The width of the catch plates —16— from front to rear and the relation of said plate to the nests is such that when the door —30— is opened, the front edge of the plate —16— will overhang the upper front edge 110 of the frame —24— to allow any deposits thereon to be readily removed without liability of falling into the nests, or, if necessary, the doors —30— and plates —16— may 115 be left in their normal positions and the roosts raised to permit the cleaning of the plate and roosts.

120 The passages leading from the ventilating chamber —12— to the interior of the compartments of the hen house are preferably provided with screens, as —34— to prevent the entrance of rodents.

125 The opening —11— in the upper portions of the front wall of the hen house is also covered by screen —34'— to provide for the necessary ventilation when the door —11'— is open.

130 Suitable feed boxes —35— are secured to the inner faces of the front walls of the

compartments directly below the openings —9— so that the attendant may easily replenish the food supply from the outside without entering the building. Each compartment is also equipped with a vegetable basket —36—, a water fountain —37— and a waste box —38—, the vegetable baskets being preferably made of screen wire and are secured directly opposite each other to 10 the partition —5— near the door —17— therein.

In like manner, the water fountains —37— are secured directly opposite to each other to the partition —5— above the floor and upon 15 suitable ledges —39— at the rear of the vegetable baskets —36—.

The waste boxes —38— are secured to the inner faces of the end walls of the hen house above the floor in line with and directly opposite each other.

The front wall of the hen house is provided near the floor line with passages —40— through which the fowls may readily pass but may be closed when desired by 25 slide doors —41—, Fig. —1—. It will be observed that all of the interior fixtures, such as the feed box, vegetable basket, waste baskets, water fountains and nests are wholly above the floor, which is therefore 30 free from obstructions and may be readily flushed or cleansed throughout its area without disturbing any of said fixtures, all of which together with the system of ventilation affords a particularly convenient and 35 sanitary hen house and at the same time allows the fowls the utmost freedom of movement and care with a minimum amount of labor.

The roosts —15— and underlying catch 40 plates —16— are provided near their free edges with eyes or staples —42— for receiving hooks, as —43—, on the lower side of the roof plate by which said roosts and plates may be held in their elevated positions while the nests are being cleaned or 45 to facilitate the cleansing of the under sides of both roosts and the plates.

It will be observed that the partitions —28— dividing the nests one from the other 50 extend some distance above the rear sides of the nest to approximate the horizontal plane of the under side of the plates —16— to support the latter in their normal horizontal planes, and allow the plates to serve 55 as covers for the nests to prevent the entrance thereto of deposits from the roosts.

What I claim is:

1. In combination with a hen house having a hollow upright wall, the inner side of 60 which terminates above the floor level to form a clean-out opening, a row of nests

within the housing some distance from and parallel with the hollow upright wall, a catch plate covering the tops of the nests and extending to the inner side of the hollow wall, and a roost above the plate in spaced relation thereto to form an intervening clean-out space, said space communicating with the chamber in the hollow wall.

2. In a hen house, the combination of a 70 housing having a hollow upright wall, the inner side of which terminates above the floor level to form a clean-out opening, and is provided with another clean-out opening at a higher level, a row of nests running 75 parallel with the hollow wall in spaced relation thereto, a catch plate extending from the lower side of the last-named clean-out opening across the top of the nests, and a roost above said last-named opening and the 80 plate in spaced relation to said plate to form a clean-out space registering with said second-named opening.

3. In a hen house, the combination of a 85 housing having a hollow upright wall, the inner side of which terminates above the floor level to form a clean-out opening, and is provided with another clean-out opening at a higher level, a row of nests running 90 parallel with the hollow wall in spaced relation thereto, a catch plate extending from the lower side of the last-named clean-out opening across the top of the nests, and a roost above said last-named opening and the 95 plate in spaced relation to said plate to form a clean-out space registering with said second-named opening, said plate and roost being hinged to the inner face of the hollow wall to swing vertically to permit access to the nests from the top and also for 100 cleaning purposes.

4. A hen house having a hollow, upright wall forming a ventilating chamber, said chamber communicating with the interior of the house through separate passages at 105 different levels, a row of nests supported within the house in a plane between said levels and provided with a hinged member adapted to swing to and from a vertical position, a catch plate hinged to the hollow 110 wall below the uppermost passage to swing vertically and having its free edge normally resting upon the free edge of said member, and a roost hinged to said hollow wall above the uppermost passage to swing 115 vertically toward and from said plate.

In witness whereof I have hereunto set my hand this 2nd day of December 1918.

WILLIAM C. CLARE.
